UNITED STATES PATENT OFFICE

114,102

DESIGN FOR A DISPLAY STAND

Raymond A. Hennings, New Orleans, La.

Application April 4, 1938, Serial No. 76,293

Term of patent 7 years

To all whom it may concern:

Be it known that I, Raymond A. Hennings, a citizen of the United States, residing at New Orleans, in the Parish of Orleans and State of Louisiana, have invented a new, original, and ornamental Design for a Display Stand, of which the following is a specification, reference being had to the accompanying drawings, forming part thereof.

I claim:

The ornamental design for a display stand, as shown.

RAYMOND A. HENNINGS.
